UNITED STATES PATENT OFFICE.

LAWRENCE M. ENDRES, OF WAUNAKEE, WISCONSIN.

DRAWBAR FOR HARROWS.

Application filed June 25, 1926, Serial No. 118,428. Renewed April 12, 1929.

This invention relates to a drawbar for harrows, and is particularly directed to a drawbar for a toothed harrow.

It is the usual practice to draw harrows across a field in sets or groups, and it has been the practice heretofore, to provide a drawbar for the entire group so that all of the harrows may be simultaneously drawn across the field. This mode of operation, however, has the defect of not permitting the same freedom that the harrows heretofore have had when drawn singly. It is impossible, for example, to draw a harrow constructed as described, through a constricted space, such as a gate, for instance.

Objects of this invention are to provide a drawbar for harrows which is so constructed that a plurality of harrows may be simultaneously pulled across a field through the medium of the drawbar, and which may be drawn through a constricted space due to the peculiar construction of the drawbar.

Further objects are to provide a drawbar for harrows which is so constructed that it will permit the folding of one harrow over the other so that although a plurality of units may be used in the normal operation of the device, nevertheless they may be folded to permit passage through constricted spaces, and to permit the ready drawing of the harrow to and from the place of work.

Further objects are to provide a drawbar for harrows which is so constructed that the draft or pull is distributed correctly for the several harrows without excessive strains and without any tendency to buckling or folding up.

Further objects are to provide a drawbar for harrows having the characteristics noted above, which may be very cheaply constructed, which is eminently practical in operation, and which is strong and rigid.

An embodiment of the invention is shown in the accompanying drawings in which:

Figure 1 shows the drawbar attached to several harrows and shows the harrows in their extended position;

Figure 2 is a rear view of the drawbar showing one of the sections folded;

Figure 3 is a detail of one of the joints of the drawbar, such view being a plan view;

Figure 4 is an elevation of one of the joints.

The drawbar consists of a central section 1 and a plurality of end sections 2. In the form shown, three sections have been illus-

trated, although obviously another number of sections may be employed.

The central section is attached to a forward bar 3, by means of bolts 4, such forward bar being held in spaced relation to the bar 1 by means of sleeves 5, or spacers positioned upon the bolts.

Further, the bars 1 and 3 are braced by means of the diagonal braces 6, as shown in Figure 1. The drawbar may be drawn across the field by means of the draft ring 7, which is joined to the bar 3 by means of the diagonal links 8. These links have their inner ends engaged by the plates 9, which are clamped beneath the nuts of the bolts 4. The other end of the plates 9 carry diagonal links 10 which form a continuation of the links 8, as may be seen from Figure 1. These links have their ends received by looped or U-shaped portions 11, which are pivotally secured to the bars 2 by means of the bolts or screws 12. It is to be noted particularly that the link 10 pivotally joins the plate 9 and may be rocked about such plate when the end bars 2 are rocked over upon the central bar 1.

The hinged joint for the section or bars 1 and 2 may comprise a pair of channel shaped members 13 which, as may be seen from Figures 3 and 4, receive the ends of the bars 1 and 2. These plates are hingedly joined by means of rivets 14 adjacent their upper portions, as shown most clearly in Figure 4. It is to be noted from reference to Figure 3 that the bolts 4 pass through the ends of the bar 1 and are securely attached thereto by means of the rear nuts.

It is to be noted from reference to Figure 4 that a plate 15 is held by means of the bolts 4 rigidly against the back of the hinged member 13 of the bar 1, at each end of such bar and that such plate, consequently, forms a bearing against which the adjacent end of the plates 13 for the end bars 2 may bear. This construction is most clearly illustrated in Figure 4.

Each of the several bars are provided with eye bolts 16 which carry links 17 by means of which the harrows 18 are attached in a floating or self-adjusting manner to permit the harrows to adjust themselves to the varying contour of the field.

It will be seen, therefore, that a very strong construction of jointed drawbar has been provided for harrows so that the har-

rows may be drawn in groups across a field under normal working conditions and may be folded one over the other in order to render the structure compact and permit its 5 passage through constricted spaces.

It will be seen further that the device may be readily constructed and may be cheaply produced.

Although the invention has been described in considerable detail, such description is intended as illustrative rather than limiting as the invention may be variously embodied and as the scope of such invention is to be determined as claimed.

15 I claim:

A drawbar for toothed harrows, comprising a central bar, a forward bar positioned

in front of said central bar, bolts and spacers joining said bars, a central draft ring positioned in front of said forward bar 20 and joined to said bolts by means of links, end bars hingedly joined to said central bar and joined to said bolts by means of links forming a continuation of said first mentioned links and extending rearwardly in 25 line with said first mentioned links, and means carried by said central and end bars for attachment to harrows.

In testimony that I claim the foregoing I have hereunto set my hand at Waunakee, 30 in the county of Dane and State of Wisconsin.

LAWRENCE M. ENDRES.
